(57) **CLAIM**

The ornamental design for a sleeved hose, as shown and described.

DESCRIPTION

FIG. 1 is a top plan view of a sleeved hose;

FIG. 2 is a bottom plan view thereof;

FIG. 3 is a left side end view thereof, the right side being a mirror image thereof;

FIG. 4 is a top plan view of the article in an alternate state of use;

FIG. 5 is a bottom plan view thereof; and,

FIG. 6 is a top plan view of the article in an alternate state of use.

The broken line showing is included for purpose of illustrating portions of the article and forms no part of the claimed design.
